Primary Examiner — Jennifer Rivard*Assistant Examiner* — JennyLou M Binas(74) Attorney, Agent, or Firm — ScienBiziP, P.C.(57) CLAIM

The ornamental design for a washing machine, as shown and described.

DESCRIPTION

FIG. 1 is a front, right and top perspective view of a washing machine, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the washing machine of FIG. 1 in a contracted state; and,

FIG. 10 is a rear, left and bottom perspective view of the washing machine of FIG. 9.

The broken lines shown in the drawings are included for the purpose of illustrating portions of the washing machine that form no part of the claimed design.
